UNITED STATES PATENT OFFICE.

DAMON GREENLEAF AND JOSEPH H. CROSBY, JR., OF JACKSONVILLE,
FLORIDA.

DESIGN FOR A KNIFE-HANDLE.

SPECIFICATION forming part of Design No. 22,860, dated October 31, 1893.

Application filed July 14, 1893, Serial No. 480,534. Term of patent 7 years.

To all whom it may concern:

Be it known that we, DAMON GREENLEAF and JOSEPH H. CROSBY, Jr., citizens of the United States, residing at Jacksonville, in the county of Duval and State of Florida, have invented and produced a new and original Design for Cutlery-Handles, of which the following is a specification, reference being had to the accompanying drawing illustrating the same.

Our invention relates to designs for knife handles.

The accompanying drawing is an illustration of a knife handle with our design thereon. The handle has a general oval, spatulate shape somewhat pointed at one end and elongated with approximately parallel edges at the other end which is adjacent to the blade.

The leading feature of our design is the representation of orange blossoms and leaves. 20

In the accompanying drawing A indicates the orange, B buds and C the blossoms, they being distributed over the surface of the knife handle in the form of a cluster or spray.

Our design is intended for the handle of 25 such articles as knives.

What we claim is—

The design for knife handles herein shown and described.

DAMON GREENLEAF.
JOSEPH H. CROSBY, JR.
